(57) **CLAIM**

The ornamental design for a massaging apparatus for forearms, as shown and described.

DESCRIPTION

FIG. 1 is a front view of a massage apparatus for forearms according to one embodiment of the present invention.

FIG. 2 is a back view of the massage apparatus of FIG. 1.

FIG. 3 is a top view of the massage apparatus of FIG. 1.

FIG. 4 is a bottom view of the massage apparatus of FIG. 1; and,

FIG. 5 is a left side view of the massage apparatus of FIG. 1.

The right side view is symmetrical to the left side view, so the right side view has been omitted.

The broken lines are for illustrative purposes only, and form no part of the claimed design.
